ROOF WINDOW.
APPLICATION FILED MAY 3, 1912.

Patented Sept. 29, 1914.

UNITED STATES PATENT OFFICE.

CLAUDE J. ALLEN, OF EARLY, IOWA.

ROOF-WINDOW.

1,112,401.

Specification of Letters Patent. Patented Sept. 29, 1914.

Application filed May 8, 1912. Serial No. 695,864.

To all whom it may concern:

Be it known that I, CLAUDE J. ALLEN, a citizen of the United States, residing at Early, in the county of Sac and State of Iowa, have invented a new and useful Improvement in Roof-Windows, of which the following is a specification.

The object of my invention is to provide a boxing and window frame for window roofs constructed entirely of sheet metal, and of simple, durable and efficient construction.

A further object of my invention is to provide means for raising and lowering a window for ventilating purposes.

15 A further object of my invention is to provide means to prevent the window from being raised from the outside.

20 A further object of my invention is to provide a window frame with means for protecting the glass in the frame against hail and the like.

25 The above and other objects, advantages and capabilities of my invention will become apparent from a detailed description 25 of the accompanying drawings, in which—

Figure 1 is a view in perspective of a device embodying my invention, Fig. 2 is a cross-sectional view of the same, and Fig. 3 is a central longitudinal sectional view of 30 the same.

My device consists essentially of a sheet-metal boxing for windows, and a sheet-metal window frame hingedly mounted on said boxing, and upright members secured 35 to said frame and provided with cross-pieces, to which is secured a screening to protect the device against hail and the like. I have used the reference numeral 10 to designate the boxing as a whole, which consists of two sides and two ends having outwardly extending flanges 11 designed to be laid under the roofing material to insure a tight joint at the place where the boxing is installed. Each one of these sides and ends 40 are constructed of a sheet metal strip having outwardly extending flanges, which are bent upwardly and downwardly substantially in U-shaped form, at substantially right angles to the outwardly extending flange, to form the sides and ends proper, as best shown in Figs. 2 and 3. The two ends of the boxing are lapped over the respective ends of the sides and are secured together by any suitable means, such as rivets, as best 45 seen in Fig. 1.

Hingedly mounted on the boxing 10 is a

window frame 12 which is constructed entirely of sheet metal and consists of two sides, two ends and a central partition. The sides and ends of said frame are constructed 60 of sheet metal strips 13 which are bent downwardly at substantially right angles, thence upwardly to a point spaced apart from the inwardly extending portion 13, then inwardly at substantially right angles 65 to said downwardly extending portion, and thence outwardly substantially in U-shaped form to form the lower casing 14 of the sides and ends of the frame. In securing the parts together, the sides are lapped over 70 the ends and secured by any suitable means, such as the rivets shown. Near the center of said frame I provide a partition which is constructed of two sheet metal strips 16, which are bent downwardly at substantially 75 right angles, thence upwardly substantially in U-shaped form to form a rib or support 17.

The upward extending portion extends 80 upwardly to a point spaced apart from the upper portion 16, and is then bent outwardly and backwardly at substantially right angles to the downward extending portion to form the lower casing 18. The upper 85 portions 16 of the partition extend entirely across the frame, the upper casing of the ends being bent upwardly to permit the upper portion of the partition to be inserted 90 thereunder. The rib or downwardly extending portion 17 of the partition is spaced 95 apart a short distance from either end so as not to interfere with the raising and lowering of the frame. The glass is securely supported in the sides and partitions, as best shown in Figs. 2 and 3.

For protecting the glass in the frame against hail and the like, I provide the window frame with uprights 19 secured to said frame in any suitable manner near either end thereof, and provided at their upper edge with cross-pieces 20, to which is secured in any suitable manner a screening 21.

For raising and lowering the window from the floor for ventilating purposes, I provide my device with a sheet metal plate 21^a pivotally mounted to the window frame at one end between the ribs 17 and provided at its opposite end with an opening designed to receive a hooked pole 22. The said sheet metal plate 21^a is provided with an opening 110 having downwardly and forwardly extending lugs 23 on its upper side. A pin 24 se-

cured to the rafter 25 is designed to be engaged by the notched openings in the plate 21^a.

It will be seen, by having the notches bent downwardly and forwardly, that the window cannot be raised from the outside. When it is desired to raise the window for ventilating purposes, all that is necessary is to push upwardly on the pole 22, sufficiently to raise the lugs 23 past the pin 24, then push upwardly on the pole 22 the desired distance, and then release the pole, and the window is then held in locked position by means of the lugs on the plate 21^a.

It will be seen from the foregoing description and drawings that I provide a roof window that eliminates many of the disadvantages of prior structures in that it does not have the disadvantage of being easily burst, as in wooden structures, and in that it does not have the expense or weight of metal or iron devices for like purposes.

While I have herein shown only one specific embodiment of my invention, it is to be understood that various changes and alterations may be resorted to by those skilled in

the art without departing from the scope of my invention, as defined in the appended claim.

Having thus described my invention, so what I claim as new and desire to secure by Letters Patent of the United States is:

In a roof window, the combination of a window frame, a sheet metal sash frame, the sides and ends of said sash frame being formed of sheet metal and bent to form upper and lower edges, a muntin for said sash frame, said muntin being constructed of two sheet metal members bent to form upper and lower edges and a pair of downwardly extending U-shaped reinforcing ribs spaced apart to receive a lifting element therebetween and a pane seated between said muntin and the respective sides and ends of said sash frame.

In witness whereof, I hereunto subscribe my name this 27 day of April, A. D. 1912.

CLAUDE J. ALLEN.
